UNITED STATES PATENT OFFICE.

GILES A. PERDUE, OF WILMINGTON, DELAWARE.

COIN-COLLECTING AND CHANGE-MAKING DEVICE.

1,399,650.

Specification of Letters Patent.

Patented Dec. 6, 1921.

Application filed October 27, 1919. Serial No. 333,621.

To all whom it may concern:

Be it known that I, GILES A. PERDUE, a citizen of the United States, residing at Wilmington, in the county of New Castle 5 and State of Delaware, have invented certain new and useful Improvements in Coin-Collecting and Change-Making Devices; and I do hereby declare the following to be a full, clear, and exact description of the 10 invention, such as will enable others skilled in the art to which it appertains to make and use the same, reference being had to the accompanying drawings, and to the letters and figures of reference marked thereon, 15 which form a part of this specification.

This invention relates to new and useful improvements in coin receiving and change making apparatus, and the object of the invention is to produce a simple and efficient 20 apparatus of this nature so arranged that when a coin is deposited in the same, the requisite change of any amount, to which the apparatus is adjusted, may be delivered.

The invention comprises various details 25 of construction, combination and arrangement of parts which will be hereinafter fully described, shown in the accompanying drawings and then specifically defined in the appended claims.

30 My invention is illustrated in the accompanying drawings which, with the numerals of reference marked thereon, form a part of this application, and in which:

Figure 1 is a perspective view of the coin 35 receiving and change making apparatus.

Fig. 1^a is a view in elevation of the apparatus.

Fig. 2 is a top plan view, parts being in horizontal section.

40 Fig. 3 is a sectional view on line 3—3 of Fig. 1^a.

Fig. 4 is a top plan view of the plate 42.

Fig. 5 is a top plan view.

45 Fig. 6 is a sectional view on line 6—6 of Fig. 1^a.

Fig. 7 is a detail perspective view of a part of the invention, and

50 Fig. 8 is a fragmentary sectional detail view of two of the magazines and the coin ejecting slides therefor.

Reference now being had to the details of the drawings by numerals:

1 designates the casing of the change making apparatus which may be of any suitable 55 size, design or shape, made preferably of

metal, having a hopper 2 at its lower end with an exit opening 3 through which the coins are delivered.

Mounted in the opposite end walls of the casing is a rock shaft 4 having a handle 5 fixed thereto, and 6 designates rods, two being shown in the drawings, which are fastened at their upper ends to collars 7 which are keyed, or otherwise fastened, to rock with the shaft 4. Said rods have right angled portions 8, having arms 9, shown clearly in Fig. 6 of the drawings, and which project horizontally, and each arm has its outer end fixed to a bar 10, shown in cross section in Fig. 6 and in edge view in Fig. 5 of the drawings. Said bar 10 has a plurality of fingers 11 projecting at right angles therefrom, and each provided for a purpose which will be hereinafter described.

Upon reference to the drawings will be seen a series of small casings, designated by numeral 12, which are secured to the rear wall of the main casing, as shown clearly in Figs. 2 and 5 of the drawings, and each casing rests upon a shelf or table 15 having a marginal flange 16, said table resting upon the upper ends of a plurality of coin receiving magazines 17, 18, 19, 20 and 21, provided for the reception of coins of different denominations.

Mounted within each of said casings 12, is a hollow shell 22, a detail of one of which is shown in Fig. 7 of the drawings, and which is provided with a cylindrical outlined horizontal opening 23 adapted to receive a finger 11. Each casing 12 has vertically disposed coin slots 24 and 24' registering with slots in said casing, the coin slots 24 registering with the containers 17, 18, 19, 20 and 21, and the coin slots 24' registering with a like number of similar coin slots or casings which discharge directly into the hopper 2.

Projecting from the rear of said shell is a pin 25, which telescopes within a hollow tubular projection 26 extending horizontally from the rear wall 14, as shown in Fig. 5 of drawing.

A coiled spring 27 fits over said hollow tubular projection and the pin 25, and bears between the shell 22 and the rear wall 14 of the casing, the purpose of said spring being to normally throw the shell 22 to its farthest forward position within the casing 12. Each of the several casings 12 contains 110

a similar shell which is operated in the same manner as before described.

Fastened to corresponding sides of each shell 12 is a right angled member 28, shown 5 clearly in Fig. 7 of the drawings, which has pivotal connection with the upper end of a tilting lever 29, which is slotted at 30 (Fig. 6) and has pivotal connection with a pin 31 which is mounted upon a bar 32 fastened 10 to the frame of the casing. The lower end of each of said levers 29, there being one, as shown, in connection with each shell 22, is pivoted to a link 33, which link in turn is pivotally connected at 34 to one arm of 15 an angle lever 35 which in turn is pivoted at 36 to the floor 37 underneath the magazines. Said lever 35 has an arm 38 which is adapted to contact with a lug 39 upon a plate 40, which latter has a circular outlined 20 aperture therein, corresponding to the size of the bore of the magazine under which it is located, and mounted to have a sliding movement upon the plate 42 which has a series of circular outlined openings 43 there- 25 in of sizes to correspond with the diameters of different denominations of coins to be held in the several magazines.

The lug 39 of the plate 40 extends down through an elongated slot 45 formed in the 30 plate 42, the latter being provided with a handle 46 at one end to facilitate its being withdrawn when it is desired to discharge all of the contents of the magazine into the hopper beneath.

35 In operation, assuming that it is desired to deposit a 50¢ piece and to receive 44¢ in change, the coin is dropped into the slot leading to the magazine 17, said coin being positioned within the casing 12 and against the 40 end of the shell 22 therein, after which the operator by rocking the shaft 4 through the medium of the handle 5, will cause the several pins 11, which are fastened to the bar 10, to move rearward through the perforations in the several casings 12. The first pin at the right coming in contact with the coin in the first casing 12, will cause the shell therein to move rearward, and, through the 45 pivotal connections 29 therewith, the angled lever 35 will be tilted, and its arm coming in contact with the lug 39 upon the plate underneath the second magazine at the right, will cause the plate having said lug to move to the left and coming in contact with the 50 next adjacent plate 40, will cause the series of plates to move simultaneously to the left.

It will be understood that each plate 40 is normally in registration with the magazine above and each adapted to receive a coin of 55 a particular denomination, the upper surface of the coin being flush with the upper surface of the plate 40, and that when the series of plates 40 are moved to the left by crowding against each other, each plate will 60 carry with it the coin of a certain denomi-

nation, and shut off the exit of other coins above, and when the circular outlined opening in each plate 40 comes in registration with an opening of similar diameter in the plate beneath, the several coins will drop 70 into the hopper at the bottom. In the event of it being desired to cause more than one coin to be deposited at the same time from a particular magazine, in order to make the proper change, the particular plate underneath the magazine, where more than one coin is to be deposited, is of a thickness, corresponding to the total thickness of the several superposed coins to be ejected from the particular magazine under which it is 80 stationed.

After pressure is relieved from the operating handle 5, the various springs 27 will return the parts to their normal positions and the apparatus will be ready for a repetition of the operation described.

In the event that a coin of a lesser denomination be placed in a slot provided for a coin of a larger denomination, it is conveyed by gravity downward to the pan underneath, 90 to be taken out by the person who inserted the same, without any effect on the mechanism. This is accomplished by means of a portion of the slots 24', immediately beneath the shells 22, having internal shoulders to 95 arrest the proper coin in position for the action of the plunger 11, the plunger contacting with the coin and pushing the same and the shell 22 rearward, until the coin comes in vertical alinement with one of the 100 magazines, such as 18, whereupon the coin drops thereto. Said shoulders, on the inside of the slots 24' are so arranged as to allow any coin of a smaller diameter to pass, but to arrest the proper coin.

105

The function of the rear chutes 24 is to provide means whereby the machine can be charged with change, or coins, direct into the mechanism, without running it through the mechanism and registering the same.

110

It will be understood, of course, that the tops of the chutes 24 will normally be covered by a lid, which can be opened only by authorized persons. The coins are dropped right through the chutes 24 into the magazines to charge the machine.

115

What I claim to be new is:

1. A coin-receiving and change-making apparatus comprising a row of magazines disposed side by side for the reception of 120 coins of different denominations, a series of horizontally movable plates, one thereof being horizontally disposed beneath each of said magazines, each of said plates having an aperture to receive a coin, said apertures 125 being adapted for coins of different denominations, said plates being disposed end to end and movable in a direction lengthwise of said row, selectively-actuated coin controlled elements horizontally slidable in a 130

plane above said magazines, and mechanism intermediate said elements and said plates for selectively moving the latter.

2. A coin-receiving and change-making apparatus comprising a row of magazines disposed side by side for the reception of coins of different denominations, a series of horizontally movable plates, one thereof being horizontally disposed beneath each of said magazines, each of said plates having an aperture to receive a coin, said apertures being adapted for coins of different denominations, said plates being disposed end to end and movable in a direction lengthwise of said row, selectively-actuated coin controlled elements horizontally slidable in a plane above said magazines, mechanism intermediate said elements and said plates for selectively moving the latter, and a stationary plate disposed beneath said series of movable plates, and having apertures therein adapted to register with said apertures in the movable plates.

3. A coin-receiving and change-making apparatus comprising a row of magazines disposed side by side for the reception of coins of different denominations, a series of horizontally movable plates, one thereof being horizontally disposed beneath each of said magazines, each of said plates having an aperture to receive a coin, said apertures being adapted for coins of different denominations, said plates being disposed end to end and movable in a direction lengthwise of said row, spring-pressed selectively-actuated coin controlled elements horizontally slidably in a plane above said magazines, mechanism intermediate said elements and said plates for selectively moving the latter, and means for automatically returning the movable parts to their normal position after actuation thereof.

4. A coin-receiving and change-making apparatus comprising a row of magazines disposed side by side for the reception of coins of different denominations, a series of horizontally movable plates, one thereof being horizontally disposed beneath each of said magazines, each of said plates having an aperture to receive a coin, said apertures being adapted for coins of different denominations, said plates being disposed end to end and movable in a direction lengthwise of said row, selectively-actuated coin controlled elements horizontally slidable in a plane above said magazines, mechanism intermediate said elements and said plates for selectively moving the latter, and a stationary casing for each of said coin controlled elements and within which casings said coin controlled elements are slidable.

5. A coin-receiving and change-making apparatus comprising a row of magazines disposed side by side for the reception of coins of different denominations, a series of horizontally movable plates, one thereof be-

ing horizontally disposed beneath each of said magazines, each of said plates having an aperture to receive a coin, said apertures being adapted for coins of different denominations, said plates being disposed end to end and movable in a direction lengthwise of said row, selectively-actuated coin controlled elements horizontally slidable in a plane above said magazines, mechanism intermediate said elements and said plates for selectively moving the latter, and a stationary plate disposed beneath said series of movable plates, and having apertures therein adapted to register with said apertures in the movable plates.

6. A coin-receiving and change-making apparatus comprising a row of magazines disposed side by side for the reception of coins of different denominations, a series of horizontally movable plates, one thereof being horizontally disposed beneath each of said magazines, each of said plates having an aperture to receive a coin, said apertures being adapted for coins of different denominations, said plates being disposed end to end and movable in a direction lengthwise of said row, selectively-actuated coin controlled elements horizontally slidable in a plane above said magazines, mechanism intermediate said elements and said plates for selectively moving the latter, and a stationary plate disposed beneath said series of movable plates, and having a longitudinally extending series of apertures therein adapted to register with said apertures in the movable plates, said stationary plate being provided with slots connecting said apertures therein, and projections carried by said movable plates and moving in said slots.

7. A coin receiving and change making apparatus, comprising a series of magazines for the reception of coins of different denominations, a separate movable plate mounted underneath each magazine and having an opening therein, a series of casings with coin slots therein, a spring pressed shell movable within each casing and having an opening therein, a rock shaft, a bar actuated thereby and having fingers projecting therefrom adapted to be inserted through openings in said casings to push a coin against one of said shells, pivotal levers connected one to each of said shells, and angle levers actuated thereby and adapted to contact with lugs upon said plates to cause one of said plates to be moved from underneath the magazine and contact with other similar plates, to cause one or more coins to be delivered from the magazine, and means for returning the several parts of the apparatus to their normal positions.

8. A coin receiving and change making apparatus, comprising a series of magazines

for the reception of coins of different denominations, a separate movable plate mounted underneath each magazine and having an opening therein, a series of casings with coin slots therein, a spring pressed shell movable within each casing and having an opening therein, a rock shaft, a bar actuated thereby and having fingers projecting therefrom adapted to be inserted through openings in said casings to push a coin against one of said shells, pivotal levers connected one to each of said shells, and angle levers actuated thereby and adapt-

ed to contact with lugs upon said plates to cause one of said plates to be moved from underneath the magazine and contact with other similar plates, to cause one or more coins to be delivered from the magazine, an apertured plate extending underneath the several magazines and upon which the individual plates are adapted to rest, and means for returning the several plates to their normal positions.

In testimony whereof I hereunto affix my signature.

GILES A. PERDUE.
